[57] CLAIM

The ornamental design for a combined nail file and writing implement clip, substantially as shown.

DESCRIPTION

FIG. 1 is a perspective view of a combined nail file and writing implement clip showing my new design;
FIG. 2 is a right side elevational view thereof;
FIG. 3 is a front elevational view thereof;
FIG. 4 is a rear elevational view thereof;
FIG. 5 is a top plan view thereof;
FIG. 6 is a bottom plan view thereof; and
FIG. 7 is a right side elevational view of a modification thereof.
